(57) **CLAIM**

The ornamental design for a D-handle sub-assembly, as shown and described.

DESCRIPTION

FIG. 1 is a front perspective view of a D-handle sub-assembly showing my new design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The claimed design comprises the elements shown in solid lines, the elements shown in dotted lines forming no part of the claimed design.
